UNITED STATES PATENT OFFICE.

GEORGE EDMAN BROWN, OF SELMA, CALIFORNIA, ASSIGNOR OF ONE-HALF
TO JACOB H. WRIGHT, OF SELMA, CALIFORNIA.

FUMIGATOR.

SPECIFICATION forming part of Letters Patent No. 723,513, dated March 24, 1903.

Application filed May 21, 1902. Serial No. 108,350. (No model.)

To all whom it may concern:

Be it known that I, GEORGE EDMAN BROWN, a citizen of the United States, residing at Selma, in the county of Fresno and State of 5 California, have invented a new and useful Fumigator, of which the following is a specification.

This invention relates to fumigators, and has for its object to provide an improved 10 apparatus of this character which is particularly adapted for introducing poisonous fumes, smoke, &c., into the holes, burrows, and nests of gophers and similar animals that burrow under the ground and destroy crops 15 and vegetation, and thereby drive out and exterminate such pests. It is furthermore designed to have all of the parts of the apparatus compactly mounted upon the fume-generator, so that the apparatus may be conveniently handled in transportation from one 20 place to another with the several parts located in position for convenient manipulation and adjustment to force the fumes from the generator into the holes, burrows, and the 25 like.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing 35 from the spirit or sacrificing any of the advantages of the invention.

In the drawings, Figure 1 is a side elevation of a fumigator constructed and arranged in accordance with the present invention. 40 Fig. 2 is a longitudinal sectional view thereof. Fig. 3 is a rear elevation of the device.

Like characters of reference designate corresponding parts in all the figures of the drawings.

45 In carrying out the present invention there is provided a generating-chamber 1, preferably in the form of a sheet-metal cylinder, which is closed at its front end and provided at its rear end with a door 2 to give access to 50 the interior of the chamber for the introduction of fuel and such material as may be em-

ployed to give off fumes—as, for instance, sulfur. This generator is supported by front and rear leg standards 3 and 4, respectively, each of which is formed from a metal strap 55 or band, which has its intermediate portion fitted and secured to the bottom of the generator, with its opposite portions bent downwardly and then upwardly to form the opposite legs, the opposite end portions of the leg-standard 4 being extended a suitable distance above the generator, so as to form braces or standards 5 for the support of the rear end of a bellows 6.

At the front of the generator and piercing 65 the top thereof there is a smoke or fume pipe 7, which is provided in its upper end with a T-coupling 8, which receives the discharge end of the bellows and forms a support therefor.

70 The bellows is arranged with its inlet upon the lower side of the bellows, and this inlet is in communication with the interior of the generating-chamber through the medium of a substantially horizontal pipe 9, which is 75 connected to a lateral rearwardly-directed nipple 10 on the short pipe 7, while its rear end, which is terminated short of the standards 5, is provided with an inverted-T-coupling 11, which is in turn connected to a nipple 12, carried by a plate 13, secured to the under side of the bellows and embracing the inlet thereof, so that the fumes and smoke 80 may be drawn through the pipes 7 and 9 and the couplings 11 and 12 into the bellows, from 85 which they are discharged through the forward end of the T-coupling 8.

To prevent the fumes from being withdrawn 90 into the bellows after they have been discharged therefrom, there is provided a valve comprising an open-ended tubular nipple or casing 14, which is fitted to the outer end of the T-coupling 8, and within which is a forwardly-tapered tubular nozzle 15, which projects beyond the forward end of the casing 95 14 and is provided with a beveled outer end that is normally closed by a flap-valve 16, hinged to the upper side of the nozzle and normally lying against the beveled end of the nozzle. A tubular coupling 17 is fitted to the 100 outer end of the valve-casing 14 and is provided with a reduced outer terminal to which

a flexible conducting-pipe 18 is connected, this pipe being of any suitable length, so as to carry the fumes to the desired point of application.

5 From the foregoing description it will be seen that the bellows is mounted upon the top of the generating-chamber 1, and the pipe for carrying off the fumes is also connected to the chamber and all of the parts are compactly 10 assembled, so that they are all conveniently accessible for adjustment and repairs, and the device may be conveniently transported without taking it apart, and it is always in readiness for use.

15 In the operation of the device a fire is built in the fire-box and sulfur or other suitable material is introduced into the door 2, so as to give off fumes through the discharge-pipe 7. The apparatus is of course placed in close 20 proximity to the hole or burrow to which the fumes are to be applied, and the open end of the conducting-pipe 18 is introduced into said hole or burrow, after which the bellows is manipulated to draw the fumes from the generator and force the same into the hole or burrow, thereby to drive out and exterminate 25 the gophers or other pests.

Should the fumes and smoke heat the bellows to a dangerous degree, cool air may be 30 admitted to the bellows by means of a removable closure-plug 19, applied to the outer or rear end of the coupling 11, so as to reduce the temperature of the smoke and fumes, and thereby avoid damaging the bellows.

35 It will be noted that the blast-pipe of the bellows extends entirely across the upper end of the pipe 7 and fits snugly the rear end of the T-coupling 8, whereby little or no fumes will be drawn in through the blast-pipe, and 40 practically all of the fumes will pass through the pipe 9 before entering the bellows.

What I claim is—

1. In a fumigator, the combination with a generating-chamber, of a T-shaped discharge-pipe connected to the generator, a pipe connected to one end of the head of the T-shaped discharge-pipe, a blast device carried by the generator with its discharge end communicating with the other end of the head of the 45 T-shaped discharge-pipe, and a passage leading from said T-shaped discharge-pipe to the inlet of the blast device.

2. In a fumigator, the combination with a generating-chamber, of an upstanding substantially T-shaped discharge-pipe piercing the top of the chamber near one end thereof, a tube connected to the outer end of the head of the T-shaped discharge-pipe, a bellows supported upon and above the generating- 55 chamber with its blast-pipe projected into the inner end of the head of the T-shaped discharge-pipe, and a pipe leading from the intermediate portion of said T-shaped discharge-pipe to the inlet of the bellows.

65 3. In a fumigator, the combination with a generating-chamber, of a substantially T-shaped discharge-pipe piercing the top there-

of, a pipe leading from one end of the head of the discharge-pipe, a bellows having its blast-tube inserted into the opposite end of the head, a standard rising from the rear end of the generator and supporting the bellows, the latter having its inlet upon the under side thereof, and a pipe located between the generator and the bellows with one end in communication with an intermediate portion of the T-shaped discharge-pipe and its opposite end connected to the inlet of the bellows. 70

4. In a fumigator, the combination with a generating-chamber having leg-standards, the rear pair of which are extended above the top of the generator, a discharge-pipe piercing the opposite end of the chamber, and a bellows supported upon the upper projected ends of the rear standards with its blast-tube 80 in communication with the discharge-pipe and its inlet in communication with the interior of the generating-chamber. 85

5. In a fumigator, the combination with a generating-chamber, of a discharge-pipe, a lateral pipe leading from the discharge-pipe, an outwardly-tapered nozzle projected within the lateral pipe and having its end beveled, a flap-valve at the outer end of the nozzle and lying over the beveled end, a coupling secured 90 to the outer end of the lateral pipe, and a conducting-pipe secured to the coupling. 95

6. In a fumigator, the combination with a combined fire-box and generator, of a blast device having its inlet in communication with the interior of the generator, and means for supplying external air to the blast device for cooling the same. 100

7. In a fumigator, the combination with a combined fire-box and generating-chamber, of a discharge-pipe, a blast device in communication with the discharge-pipe, a passage 105 communicating between the inlet of the blast device and the discharge-pipe, and means carried by said passage for introducing external air thereto to prevent overheating of the blast device. 110

8. In a fumigator, the combination with a combined fire-box and generator, of a substantially T-shaped discharge-pipe piercing 115 the same, a bellows having its blast-tube in communication with one end of the head of the discharge-pipe, with its inlet upon the inner side of the bellows, a coupling fitted to the inlet of the bellows, a pipe leading from the intermediate point of the discharge-pipe to the coupling, and a removable closure for the coupling. 120

9. In a fumigator, the combination with a combined fire-box and generator, of a substantially T-shaped discharge-pipe rising 125 from one end thereof, a bellows having its blast-tube projected into the rear end of the head of the discharge-pipe with its inlet upon the under side thereof, means for supporting the rear end of the bellows upon the generator, an inverted substantially T-shaped coupling fitted to the inlet of the bellows, a removable closure-plug for the outer end of the 130

coupling, a pipe leading from an intermediate portion of the discharge-pipe to the inner end of the coupling, a tubular casing fitted to the outer end of the head of the discharge-pipe, an outwardly-tapered nozzle carried within the casing and projected at the outer end thereof, a flap-valve for the outer end of the nozzle, a movable coupling fitted to the casing and inclosing the outer end of the noz-

zle, and a flexible tube connected to the coupling.

In testimony that I claim the foregoing as my own I have hereto affixed my signature in the presence of two witnesses.

GEORGE EDMAN BROWN.
